JAMES R. DENKERT, OF JOHNSTOWN, NEW YORK

INFLATABLE PLAYING BALL AND BLADDER THEREFOR

Application filed January 25, 1930. Serial No. 423,307.

My invention consists in the novel features hereinafter described, reference being had to the accompanying drawing which illustrates one embodiment of my invention selected by me for purposes of illustration, and the said invention is fully disclosed in the following description and claims.

My invention relates to an inflatable playing ball comprising an exterior cover and an inflatable bladder, and consists in the novel features whereby the valve mechanism is secured to the inflatable bladder, and the inflatable bladder permanently secured to the cover in operative relation to a minute inflating aperture therein.

In the construction of such playing balls, which are used in playing foot ball, hand ball, and other games, it is desirable that the bladder should be capable of inflation through a minute aperture only large enough to receive the nozzle of a small air pump, and that the bladder shall be rigidly connected with the cover so as to maintain it at all times in proper relation to the cover when inflated, and to hold the valve mechanism in co-axial relation with the minute hole in the cover. It is also necessary that the valve sleeve, which is ordinarily constructed of metal, and provided with a dust cap or closure, should be held at such a point below the exterior surface of the cover that it will not strike the ground or any part of the bodies of the players, while at the same time it is highly important that the resiliency of that portion of the ball immediately adjacent to the metallic valve mechanism should have substantially the same resiliency as other portions of the ball, in order not to prevent an abnormal rebound of the ball when this portion of it strikes the ground or other object.

In carrying out my present invention, I provide the elastic bladder, which is usually formed of rubber sheet material, with a rubber valve enclosing sleeve, preferably made integral with or vulcanized to the bladder, and containing the usual metallic valve sleeve and valve. The enclosing sleeve projects beyond the adjacent wall of the bladder, forming a neck which terminates in an integral transversely disposed attaching and cushion-

ing disc, preferably provided with stitch receiving apertures, by means of which it may be directly and permanently attached to the cover, so as to hold the valve co-axially with the minute inflating aperture. The outer face of the disc is provided with a recess coaxial with the valve sleeve, which sleeve terminates at its upper end adjacent to the bottom of the recess, this recess providing room for the dust cap or closure and holding it below the surface of the ball.

When the bladder is inflated, it will be forced into contact with the neck portion of the enclosing sleeve and into contact with the inner face and marginal edges of the attaching means for permanently securing the bladder to the cover, and also providing a body of rubber surrounding the outer end of the valve sleeve and interposed between the bladder and the cover for some little distance around the valve sleeve, and thus substantially equalizing the resilience of the portion of the ball adjacent to the metallic valve with other portions, so as to insure the true bouncing of the ball when struck adjacent to the valve, while obviously the bladder can be inflated or deflated through the minute opening, provided in the cover and without disturbing any laced portion with which the ball may be provided.

In the accompanying drawing, which illustrates one embodiment of my invention selected by me for purposes of illustration,

Fig. 1 represents a foot ball embodying the invention and partly broken away to show in section the position of the parts adjacent to the valve mechanism when the bladder is fully inflated.

Fig. 2 is an enlarged sectional view of a portion of the cover and bladder adjacent to the valve mechanism, showing the bladder deflated.

Fig. 3 is an elevation showing the enclosing sleeve and valve sleeve detached.

Fig. 4 is a sectional view illustrating a mold which I conveniently employ in the formation of the enclosing sleeve.

Fig. 5 is a sectional view of the sleeve and valve provided with the usual reinforce or saddle vulcanized thereto.

Fig. 6 is a top plan view of the valve enclosing sleeve looking downward upon the upper face of the disc.

Fig. 7 is a view partly in section, showing a slight modification of the enclosing sleeve.

Referring to the drawings, 1 represents the outer cover of the ball formed preferably of leather segments stitched together in any usual or preferred manner. The cover may 10 be provided with the usual hand aperture or slit, indicated at 2, between adjacent segments, the edges of which are drawn together by lacings, 3, or secured in any other desired manner. The cover is also provided with a 15 minute inflating aperture, indicated at 4, preferably located at a distance from the hand aperture, where that is provided, and being only of such size as to permit the insertion of the exteriorly threaded nozzle of a 20 small air pump, such as a hand bicycle pump, or other suitable device. The main body of the bladder, which is indicated at 5, is of any usual or preferred construction, and is provided at one point with a valve opening, indicated at 6 in Fig. 2. I prefer to employ a 25 valve mechanism somewhat similar to the well known Schrader valve, comprising a valve casing, indicated at 7, and the usual interior valve mechanism, the details of which have no bearing on my present invention. As a matter of fact, any usual or preferred 30 form of valve mechanism so constituted may be employed. The valve casing, 7, is provided at its upper end with the usual interiorly threaded portion, 7^a, to receive the usual closure or dust cap, 8, but the exterior portion of the valve is preferably unthreaded as shown, although the valve casing may be 35 provided on its outer surface with projecting portions, as indicated at 7^b, to form a more secure bond with the enclosing sleeve. 10 represents the enclosing sleeve, which is preferably molded around the valve sleeve, and has a portion extending within and a portion 40 projecting from the bladder. This outer projecting portion forms a neck, 11, terminating at its outer end in the attaching and cushioning disc, 12, which is preferably circular, but which may be of any other desired shape, 45 and is preferably of greater thickness than the wall of the cover, 1. The upper face of the disc is provided with an annular recess, indicated at 13, to accommodate the dust cap, the outer wall of the recess flaring somewhat, 50 to facilitate the removal of the cap, so that the outer end of this recess is slightly larger in diameter than the inflating aperture, 4, in the cover. The valve casing, 7, has its upper end located at substantially the bottom of the recess, 13, as shown, and the disc, 12, is preferably provided with stitch receiving apertures, indicated at 14, to facilitate securing the disc to the cover by means of stitches, indicated at 15, of any suitable material.

In Fig. 4, I have shown a convenient form

of mold whereby the enclosing sleeve can be molded and vulcanized upon the valve casing, 7. In this instance the mold comprises an upper member, 16, having an aperture, 17, therein, to receive a pin, 18, having at its lower end a threaded portion, 19, which can be screwed into the interiorly threaded portion of the valve casing, 7, so as to hold the valve casing in axial alignment with the recessed portions of the mold and in proper relation to the enclosing sleeve which is to be formed thereon. The lower mold member is indicated at 20, and this member is provided conveniently with pins, indicated at 21, having portions, 22, projecting into the portion of the recess in the upper mold member, corresponding with the attaching and cushioning disc, 12, so as to form the apertures, 14, therein. The rubber stock is fed to the mold and molded and vulcanized therein around the valve casing, 7, in the usual manner, and as clearly indicated in Fig. 4, thus permanently attaching the valve casing within the enclosing sleeve. The enclosing sleeve and valve casing are shown in Fig. 3 as they would appear when removed from the mold. I prefer to provide the attaching sleeve with the usual reinforcing flap or saddle, indicated at 23. While this part could be molded integrally with the sleeve, it will usually be more convenient to form it separately in the usual manner and to force the sleeve through the central aperture in the reinforcing flap or saddle, indicated at 24, so as to bend the marginal portions of the aperture downwardly around the sleeve, 10, as shown in Fig. 5, and the sleeve and flap are then preferably vulcanized together. The portion of the enclosing sleeve, 10, below the flap or saddle, is then inserted in the hole, 6, of the bladder, and the adjacent portions of the bladder and the reinforcing flap, 23, are vulcanized together, as shown best in Fig. 2. It will thus be seen that the bladder and the reinforcing sleeve with its attaching disc are in effect integral and are all composed of rubber, and that the metallic valve casing is firmly seated in the enclosing sleeve.

The outer face of the disc, 12, is now brought into contact with the inner face of the cover, so as to bring the valve sleeve, 7, into co-axial relation with the aperture, 4, in the cover, and the disc, 12 is directly and permanently secured to the cover in that position, preferably by stitching through the holes, 14, provided in the disc, 12, for that purpose. When the disc is so attached, it will be seen that the rubber bladder is secured permanently within the cover, and that it will be held against any tendency to shift with respect to the cover, thus holding the valve casing at all times in co-axial relation with the inflating aperture, 4. When it is desired to inflate the bladder, it is only necessary to remove the dust cap, 8, insert the

nozzle of the air pump, and force air into the bladder until the desired pressure is obtained. As the bladder distends into contact with the cover, the portions adjacent to the valve will be pressed by the interior air pressure upwardly around the neck, 11, and into contact with the inner face of the disc, 12, and the exterior marginal edges of the disc. As shown in Fig. 1, it will thus be seen that when the bladder is inflated, the portions around the valve will tend to force the cushioning and attaching disc against the portion of the cover immediately surrounding the inflating aperture, 4, thus giving a yielding outward pressure against those portions of the cover which are substantially equal to the pressure of air within the entire bladder, and making this portion of the ball as resilient as any other portion. At the same time it will be noted that all the metal parts, including the valve casing and the dust cap, are below the cover, and being embedded in the sleeve, are cushioned in all directions, so that there is no possibility of injury to the players or to the ball from the presence of the metallic valve sleeve and dust cap. After the ball is inflated, the dust cap is screwed into place in the usual manner and will occupy a position within the recess, 13, of the attaching and cushioning disc.

In Fig. 7, I have shown a slight modification in which the outer face of the disc, indicated at 112, is provided with a facing of cloth or other fabric, 112^a, and the stitch receiving apertures, 114, extend through the disc and also through this reinforcing fabric. This construction may be desirable in some instances to assist in preventing the stitching from pulling out, or cutting the rubber, the other parts illustrated in Fig. 7 corresponding with those shown in the other figures are given the same reference numerals with the addition of 100.

Should it become necessary to repair or replace the bladder, it will ordinarily be returned to the manufacturer for this purpose, although this is not absolutely essential. In this connection it is to be noted that in repairing or replacing the bladder, the stitches connecting the disc with the leather casing will be cut, permitting the removal of the bladder through the usual laced hand opening where that is provided, which will leave stitch holes in the cover in exact alignment with the stitch receiving holes provided in the disc. In the assembling and vulcanizing together of the various parts of the bladder, the disc will preferably be uniformly positioned with respect to the body of the bladder, so that the manufacturer may either repair the bladder removed from a ball, or insert a new one, and in either case by bringing the stitch receiving apertures in the disc into registration with the stitch holes in the cover from which the cut stitches have been

removed, the repaired bladder or the new bladder, as the case may be, can be restitched to the cover through the stitch holes in the disc and the original stitch holes in the leather cover, thus securing the replaced or new bladder with the valve in exact axial alignment with the inflating aperture, and also holding the bladder in proper position with respect to the main body of the cover. In this way all friction between the bladder and the seams of the casing, which might otherwise occur and cause the bladder to burst when the ball is again used, is avoided. It will be seen that the provision of properly positioned stitch apertures in the attaching and cushioning disc contributes largely to the correct positioning of the bladder with respect to the casing and the inflating aperture therein.

What I claim and desire to secure by Letters Patent is:—

1. In an inflatable playing ball, the combination with a cover provided with a minute inflating aperture, of a bladder of rubber provided with a rubber valve enclosing sleeve having portions projecting from the bladder and provided at their outer end with a laterally extending rubber attaching and cushioning disc, provided with a plurality of stitch receiving apertures and stitched therethrough directly and permanently to the inner face of said cover adjacent the aperture, substantially co-axially with respect to said aperture, and valve mechanism, including a metallic valve sleeve, secured within said enclosing sleeve and out of contact with the cover.

2. In an inflatable playing ball, the combination with a cover provided with a minute inflating aperture, of a bladder of rubber provided with a rubber valve enclosing sleeve having portions projecting from the bladder and provided at their outer end with a laterally extending rubber attaching and cushioning disc directly and permanently secured to the inner face of the cover adjacent the aperture, substantially co-axially with respect to said aperture, said disc having a recess in its upper face co-axial with said sleeve, and valve mechanism, including a metallic valve sleeve, secured within said enclosing sleeve and having its upper end terminating adjacent to the bottom of said recess, and a dust cap for said valve sleeve adapted to lie within said recess.

3. In an inflatable playing ball, the combination with a cover provided with a minute inflating aperture, of a bladder of rubber provided with an integral rubber valve enclosing sleeve having portions projecting outside of the bladder to form a neck and terminating in an integral attaching and cushioning disc provided with a recess co-axial with the sleeve and having its marginal portions provided with stitch receiving apertures,

said disc being permanently secured by stitches to the cover adjacent the aperture, valve mechanism, including a metallic valve sleeve, secured within said enclosure sleeve, and having its outer end terminating adjacent to the inner end of the recess in said disc.

4. A rubber bladder for inflatable playing balls provided with a rubber valve enclosing sleeve projecting therefrom to form a neck 10 and terminating in a resilient integral attaching and cushioning disc, said disc being provided with a plurality of stitch receiving apertures located at a distance from the axis of the sleeve and in predetermined positions 15 with respect to the body of the bladder, an inflating valve carried by said sleeve, an outer cover surrounding the bladder and provided with a minute inflating aperture, and stitches extending through the stitch receiving apertures of the disc adjacent the inflating aperture and stitch apertures in the cover registering therewith, and holding the bladder in proper relation with said cover and the inflating valve in co-axial relation with said inflating aperture, whereby the removal and replacement of a bladder is facilitated.

5. In an inflatable playing ball the combination with a cover provided with a minute inflating aperture, of a rubber bladder provided with a rubber valve enclosing sleeve and an attaching and cushioning disk on said sleeve exterior to the bladder wall and provided with a bore co-axial with and of substantially the same diameter as the sleeve bore 35 said cushioning disk being permanently and immovably connected to the cover with its bore registering with said inflating aperture and a metallic valve secured within said sleeve and projecting into said cushioning disk and terminating within said disk and held thereby at a distance from the exterior of the surface of the cover so as to prevent interference with the resiliency of the ball.

6. A rubber bladder for inflatable playing balls provided with a rubber valve enclosing sleeve and an attaching and cushioning disk secured on said sleeve exterior to the bladder wall and provided with a bore co-axial with and of substantially the diameter of the sleeve bore, and a metallic valve secured within said sleeve and projecting into said disk and terminating within said disk said valve having an interiorly threaded outer end for the reception of an inflating pump.

7. A rubber bladder for inflatable playing balls provided with a rubber valve enclosing sleeve and an attaching and cushioning disk secured on said sleeve exterior to the bladder wall and provided with a bore co-axial with and of substantially the diameter of the sleeve bore, and with a recess in the exterior face thereof co-axial with its bore and of greater diameter, and a metallic valve secured within 65 said sleeve and projecting into the bore of said

disk said valve having its outer end terminating at the base of said recess and provided with an interiorly threaded pump receiving portion.

In testimony whereof I affix my signature. 70
JAMES R. DENKERT.
